UNITED STATES PATENT OFFICE.

EDWIN C. WASHBURN, OF MINNEAPOLIS, MINNESOTA.

DESIGN FOR A BOLT.

SPECIFICATION forming part of Design No. 30,783, dated May 16, 1899.

Application filed March 30, 1899. Serial No. 711,186. Term of patent 7 years.

To all whom it may concern:

Be it known that I, EDWIN C. WASHBURN, a citizen of the United States, and a resident of the city of Minneapolis, county of Hennepin, State of Minnesota, have invented and produced a new and original Design for a Bolt, of which the following is a specification, reference being had to the accompanying drawings, forming a part thereof.

10 Figure 1 is a plan view of the bolt involved in my special design. Fig. 2 is a view in side elevation, showing the said bolt. Fig. 3 is a view in side elevation of the parts shown in Fig. 2, looking at the same ninety degrees from the side shown in Fig. 2; and Fig. 4 is a bottom plan view of the said bolt.

15 By reference to the said drawings it will be seen that the bolt 2 is round and that the bolt-head 1 projects from the bolt 2 at three 20 sides and terminates approximately in line with the bolt at its fourth side. On its projecting sides the bolt-head is rounded off,

while at its fourth side 1^a it is formed flat and perpendicular. The sides of the bolt-head that extend approximately at right angles to the side 1^a are also slightly flattened, as best shown in Figs. 2 and 3. The general outline of the bolt-head is best illustrated in Fig. 1, and the relative position of the said bolt-head with respect to the bolt is best illustrated in Fig. 4.

25 The above design gives to the bolt a very unique and novel appearance.

Having described my invention, what I claim, and desire to secure by Letters Patent 30 of the United States, is—

The design for a bolt substantially as herein shown and described.

In testimony whereof I affix my signature in presence of two witnesses.

EDWIN C. WASHBURN.
